UNITED STATES PATENT OFFICE

2,568,469

ROOFING

Frederick A. Sunderhauf, Rutherford, N. J., assignor to Reynolds Metals Company, Richmond, Va., a corporation of Delaware

Application January 6, 1948, Serial No. 705

1 Claim. (Cl. 108—13)

1

The present invention relates to a type of roofing adapted to be handled and applied from rolls, and which may be readily laid longitudinally on a roof, interlocking of contiguous strips of the roofing being obtained by marginal seaming. My roofing is so formed as to enable its manufacture from relatively light aluminum or other light metallic sheets, and the folding thereof 180°, in a seaming fold, without fracture even when the metal is of such character as not to resist such fracture in usual fold-seaming. The roofing embodies, in its preferred form, a ribbed facing which extends across the seaming fold lines and strengthens the said lines, and at the same time, provides a desirable rigidity to the roofing as a whole, together with a pleasing texture. As stated, my roofing, at its lines of seam-forming fold is of special formation, not only to enable safe folding in the use of relatively fragile metallic sheets, but to provide, incidental thereto, registration abutments for contiguous sheets.

The invention is particularly applicable to light weight aluminum sheets of which sheets having a gauge of .010" is an example, and with such sharp seaming folds as to fracture certain of the sheets in the absence of my fold-line formation. Inasmuch as aluminum and aluminum alloys are ideal roofing materials because of ease in handling due to lightness in weight, its lower labor cost in application, its lower maintenance cost due to elimination of required painting, its reflection of the greater part of radiant heat in summer, and its generally long life, my invention affords a major extension in the use of light aluminum sheet or strip in the roofing field.

The invention will be described with reference to the accompanying drawings, in which:

Figure 1 is a plan view, broken away, showing part of a metallic sheet or strip of my invention;

Figure 2 is a transverse vertical section taken on the line 2—2, Fig. 1, and hence through one of the seaming-fold lines;

Figure 3 is a fragmentary view in perspective showing an end area of a roofing strip, as from a roll of my roofing, applied to a roof shown in dotted lines so that it projects over an end and a side of the roof, the roofing being folded under the roofing side ready for nailing;

Figure 4 shows a succeeding roofing strip placed in initial position and temporarily nailed down ready for folding over of a seaming flap carried by the first sheet at its upper margin;

Figure 5 is a view similar to Figure 4 showing the last named fold nailed down and a second strip or sheet ready for folding upwardly 180°;

2

Figure 6 is a view similar to Figure 5 showing the second sheet folded upwardly and the sheet at the corner of the roofing tucked preliminary to folding the seamed edges of contiguous roofing sheets or strips over and under the edge of the roof for nailing thereto;

Figure 7 is a view similar to Figure 6 showing three of the roofing sheets or strips in final position;

10 Figure 8 is a fragmentary perspective view showing the ridge area of a roof, a plurality of my roofing sheets or strips being shown in section;

15 Figure 8a is a perspective view of a suitable ridge cap.

Referring to the drawings, and particularly Figures 1 and 2, it will be seen that my roofing consists of sheets or strips, and preferably a roll of strip which has two reversely formed marginal areas, in that one margin is inwardly bounded by an upwardly directed channel rib 1xx, whereas the second margin is inwardly bounded by a down-turn channel-rib 1xx, the roofing as a whole being indicated at 1. The roofing is faced 20 with ribs which extend across the channel ribs, in my preferred form of the roofing.

It is highly desirable that my roofing be made of aluminum strip of such light gauge, say, .010" as to be rolled and handled in that form. Not 25 only may a given roof surface be covered as quickly with my aluminum strip or sheet roofing as with composite rolled roofing now generally sold and incorporating asphaltic materials, but my roofing will be substantially lighter, of far better appearance and long life, with substantially no cost of maintenance.

As indicated in Figure 4, the seaming-fold channel ribs are of substantial depth and inwardly bound the margins of my roofing strip or sheet. When the roof covering is started at 30 the eaves or base of the roof, as customary, a roll of my roofing may be placed so that it may be unrolled from edge to edge of the roof in such manner that at the edge of the roof, the down-turned channel rib 1xx will lie immediately above the roof edge, whereas the upturned channel rib 1xx will be above the same. Also the end of the roofing strip may project beyond the edge of the roof.

35 With an initial strip of the roofing in position at and over the roof edge, the lower margin a may be bent down vertically and thence turned under the roof for nailing as shown in Fig. 3. After nailing the initial roofing strip the second strip is applied.

As shown in Fig. 4, the second strip is inverted in the sense that it will initially lie with its normal under-face exposed. Its channel rib Ixx will be downward and its rib Ix will project upwardly, an edge of said second strip abutting the upstanding channel rib Ix of the initial roofing strip.

When the two strips lie in the position of Fig. 4, the second and overlying strip may be tacked rearwardly of its channel rib Ix , as by the tacks I , these tacks passing through the initial underlying strip and serving to hold the assembly in connection with the roof surface 3 . The next step will be the folding of the projected upper margin of the lower strip to the position of Fig. 5 and the nailing thereof down to the roofing 3 by nails which preferably are spaced approximately four inches apart. The said folding involves movement of the metal approximately 180° .

In said folding the metal moves on what may be considered as three linear areas of fold, instead of a single line of fold as with ordinary scoring, these linear areas being along each side of the channel rib and along the apex of the rib. This distribution of the folding movement of the metal prevents fracture of even relatively brittle metallic alloy sheets of relatively thin gauge.

Exact registration between the strips is secured because the channel ribs preferably project to a height at least twice the thickness of the strip and preferably a multiple of three times or more of said thickness.

With the assembly of strips as shown in Fig. 5, the upper strip is swung to the position of Fig. 6 ready to receive a third strip and continuation of the method of laying successive strips, as before.

At the corner of the roof the metal may be tucked in as shown at 5 , Fig. 5, and the projected strips at the end of the roof may be folded down and thence under the edge of the roof as indicated in Fig. 7, ready for nailing.

As shown in Fig. 8, one of the uppermost strips is bent over the ridge, and at the opposite side of the latter a strip is bent back upon itself at the margin thereof, the assembly being nailed down as by the nails I . The ridge can be capped with a ridge piece 8 , which may be of aluminum, although this is not essential.

It will be understood that various modifications may be made in the form and arrangement of the elements constituting the embodiment of the invention illustrated in the drawings, without departing from the spirit of the invention. For example the "metallic strip" may be unitary or in lamination with one or more non-metallic webs.

What I claim and desire to secure by Letters Patent is as follows:

A method of applying a roof covering formed as a metallic strip having opposed longitudinal margins, one of the margins being bounded by deformation of the metal into a rounded channel rib having a height above the face of the metal substantially greater than the thickness of the metal, said strip having its opposite margin bounded by a like channel rib projected in a direction opposite that of the first named rib, which method consists in laying a first strip upon a support with the rib of its channel rib projected upwardly, laying a second like strip over the first strip with its longitudinal edge abutting the outwardly directed channel rib of the overlying strip and with the rib of its channel rib projected upwardly, thence folding over the margin of the first strip to abut the margin of the second strip adjacent the rounded projected rib of the latter, tacking said margins of the superposed strips to the underlying support, and thence folding over the second strip into abutment with said support, whereby as to each strip the metal is moved on a plurality of linear areas of fold within each channel rib to provide distribution of the folding movement of the metal to prevent fracture thereof and the folding is in the direction of projection of each channel rib.

FREDERICK A. SUNDERHAUF.
